US0D1055970S

(12) **United States Design Patent** (10) Patent No.: **US D1,055,970 S**
(45) Date of Patent: ** Dec. 31, 2024

(54) **DISPLAY SCREEN OR PORTION THEREOF
WITH ICON**

- (71) Applicant: **Biosense Webster (Israel) Ltd.**, Yokneam (IL)
- (72) Inventors: **Natan Sharon Katz**, Atlit (IL); **Benjamin Cohen**, Haifa (IL); **Oshrat Ben Zaken**, Shimshit (IL)
- (73) Assignee: **BIOSENSE WEBSTER (ISRAEL) LTD.**, Yokneam (IL)
- (**) Term: **15 Years**
- (21) Appl. No.: **29/852,321**
- (22) Filed: **Sep. 6, 2022**

CLAIM

The ornamental design for a display screen or portion thereof with icon as shown and described.

DESCRIPTION

The FIGURE is a front view of a display screen or portion thereof with icon in accordance with our new design. The broken lines at the perimeter of the drawings illustrate a display screen and form no part of the claimed design. The remaining broken lines illustrate portions of an icon/a graphical user interface and form no part of the claimed design.
